UNITED STATES PATENT OFFICE.

ROBERT C. ZANNOH, OF MILWAUKEE, WISCONSIN.

GUIDE STRIP.

Application filed January 26, 1928. Serial No. 249,563.

This invention relates to guide and divider strips for concrete floors, walls, or ceilings particularly of the terrazzo or terrazzo mosaic type.

5 Terrazzo floors ordinarily comprise a lower layer of concrete laid upon an appropriate foundation and forming a suitable base for the reception of a top or finish layer to which coloring matter, broken marble, or other material is or has been added for decorative purposes. The top layer is ordinarily divided by strips of brass or the like into separate contiguous blocks, sometimes of rectangular or other regular contour to provide definite lines 10 of cleavage for relieving internal stresses caused by settling, shrinking, or general distortion, and sometimes of curved or other irregular contours intermeshing to form designs of various configurations. The strips 15 are ordinarily pressed edgewise into interlocking relation with the lower layer (while the same is still green) leaving exposed marginal portions projecting outwardly from the surface of the lower layer, a distance substantially equal to the depth of the top layer 20 which is thereafter applied.

Strips heretofore designed for this purpose have ordinarily included substantially horizontal wing portions arranged to abut the top 25 face of the lower layer to provide positive stops for limiting the depression of the strips into that layer. Such wings were heretofore deemed necessary in order that the strips may serve as an accurate depth gauge for the top 30 layer. In the finished floor however they lie within the plane of union between the two layers and exert a prying action therebetween tending to loosen and separate the layers.

An object of the present invention is the 35 provision of an improved guide and dividing strip of simple and economical design which is free from the above objection and otherwise entirely satisfactory for the purposes mentioned.

40 Other more specific objects and advantages will appear from the following description of two illustrative embodiments of the present invention.

In the accompanying drawings:

45 Figure 1 is a perspective view of a portion of a guide strip constructed in accordance with the present invention.

Fig. 2 is a top plan view.

Fig. 3 is an enlarged sectional view on the line 3—3 of Figure 1, showing the strip in position within a terrazzo floor.

55 Fig. 4 is a side elevation of a guide strip of modified form.

Fig. 5 is an enlarged sectional view on the line 5—5 of Figure 4.

60 The strip shown in Figures 1 to 3 is of flexible material, preferably brass, the upper portion 10 thereof being unbroken so as to provide an impenetrable divider for the top layer *a* of the floor. The upper edge 11 of the strip 65 is substantially straight and is intended to lie flush with the exposed surface of the floor, as indicated in Figure 3. The lower portion 12 of the strip is deformed in order to provide a secure anchorage within the lower layer *b*, 70 and to form a gauge for cooperation with the top surface of the lower layer to determine the proper elevation of the upper edge 11 of the strip. To this end a series of longitudinal bars 13 are pressed out of the body of the 75 strip immediately below the top portion 10 thereof. The upper edges 14 of these bars lie in a common plane parallel with the upper edge 11 of the strip and at a distance therefrom equal to the depth of the top layer *a* 80 of the floor. These bars are preferably of arched form, as clearly indicated in Figure 2, and the several bars of a series preferably project alternately in opposite directions from the plane of the strip. A second series 85 of longitudinal bars 15 are also pressed out of the body of the strip, each bar 15 being disposed immediately below and co-extensive with a bar 13. Each pair of contiguous bars 13 and 15 project in opposite directions from the plane of the strip so that the top edge 16 90 of each lower bar 15 is well spaced from the lower edge 17 of the associated bar 13 to permit an easy flow of the floor material therebetween. The lower series of bars 15 are also preferably of arched form and extend downwardly to and including the lower edge 18 of the strip. These bent portions occurring at intervals in the lower edge 18 of the strip increase the base area of the strip and 95 thus serve to sustain the strip in the upright portion shown in Figure 3.

100 In laying the floor the lower layer *b* of appropriate thickness is first applied to the

foundation layer *c* and, while the layer *b* is still green, the strip is pressed edgewise thereinto until the top edges 14 of the bars 13 are flush with the top surface of the layer *b*.
 5 Ordinarily the thickness of the layer *b* is such that when the strip is in this position it rests upon the foundation layer *c*, although this is not invariably the case. As the strip is thus inserted into the layer *b* the material thereof flows over the top edges 16 of the bars 15 to securely lock the strip against rising. After the strips have been thus positioned the top layer *a* is applied, the upper edge 11 of the strip serving as a gauge for the
 10 top surface thereof.

The strip shown in Figures 4 and 5 is similar in many respects to that hereinabove described. The upper portion 10' thereof is unbroken and terminates in a substantially straight upper edge 11'. A series of longitudinal bars, one of which is shown at 13', are pressed laterally out of the strip immediately below the upper portion 10', each bar having an upper edge 14' disposed within a plane
 20 parallel with edge 11' and at a distance therefrom equal to the depth of the top layer of the floor. A second series of similar bars, one of which is shown at 15', are pressed laterally in the opposite direction out of the strip, immediately below the bars 13' and coextensive therewith. Each bar 15' is adapted to be embedded within the lower layer of the floor, in the manner hereinafter described, to provide a secure anchorage therewith. In these
 30 respects this strip is similar to the one first hereinabove described. It will be noted however that the bars 13' and 15' are somewhat narrower than the corresponding bars 13 and 15 of the first described strip and that each
 40 of the lower bars 15' are spaced from the lower edge 18' so as to leave a substantially straight bar 19 therebetween. The upper edge 20 of each bar 19 is well below the top of the lower layer of the floor, so as to form an
 45 additional anchorage for the bar. In fact in inserting the strip edgewise into the lower layer of the floor the lower edges of the bars 13' and 15' tend to force the material of the lower layer over the edge 20 so as to completely embed the same.

Various changes may be made in the embodiment of the invention hereinabove described without departing from or sacrificing any of the advantages of the invention as defined in the appended claims.

I claim:—

1. A laterally flexible guide strip for use in multi-layer cement structures, said strip having a substantially straight upper edge, 60 a series of longitudinally extending bars pressed laterally out of said strip intermediate the upper and lower edges thereof, said bars being positioned to provide a gauge for marking the plane of union between adjacent layers, and a second series of longitudinally

extending bars pressed laterally out of said strip, the upper edges of said last named bars being lower than the upper edges of said first named bars to permit embedding thereof in a lower layer and thereby provide 70 a firm anchorage for said strip.

2. A laterally flexible guide strip for use in multi-layer cement structures, said strip having a substantially straight upper edge, a series of longitudinally extending bars 75 pressed laterally out of said strip, said bars being uniformly spaced from said upper edge to provide a gauge for marking the union between successive layers, and a second series of bars pressed out of said strip, the upper edges of said last named bars being disposed below the upper edges of said first named bars to permit embedding thereof in a lower layer and thereby provide a firm anchorage 80 for said strip.

3. A laterally flexible guide strip for use in multi-layer cement structures, said strip having a substantially straight upper edge, a series of longitudinally extending bars pressed laterally out of said strip and uniformly spaced from said upper edge to provide a gauge for marking the union between successive layers, and a second series of longitudinally extending bars pressed laterally out of said strip below said first mentioned 95 bars to permit embedding thereof in a lower layer and thereby provide a firm anchorage for said strip.

4. A laterally flexible guide strip for the purposes mentioned having a substantially straight upper edge, a series of longitudinally arched bars pressed laterally out of said strip below said upper edge and extending substantially parallel thereto, and a second series of longitudinally arched bars pressed laterally in the opposite direction out of said strip below said first named bars.

5. A laterally flexible guide strip for the purposes mentioned having a substantially straight upper edge, a series of longitudinally arched bars pressed laterally out of said strip below said upper edge and extending substantially parallel thereto, and a second series of longitudinally arched bars pressed laterally out of said strip below said first named series, each bar of said second series being contiguous to, coextensive with, and projecting oppositely with respect to a bar of said first named series.

6. A laterally flexible guide strip for the purposes mentioned having a series of bars pressed laterally out of said strip intermediate and parallel with the upper and lower edges thereof, and a second series of bars pressed laterally out of said strip below said first named series, said last named bars extending into and including the lower edge of said strip.

7. A laterally flexible guide strip for the purposes mentioned having substantially 130

straight upper and lower edges, a series of bars pressed laterally out of said strip intermediate and parallel with said upper and lower edges and, a second series of similar bars pressed laterally out of said strip between said first named series and the lower edge of said strip, each of said last named

bars being contiguous to, coextensive with, and projecting oppositely with respect to a bar of said first named series.

10

In witness whereof I hereunto subscribe my name this 23d day of January, 1928.

ROBERT C. ZANNOH.
